CLAIM

The ornamental design for a device utilized in converting electrical meter rate to currency rate, as shown and described.

DESCRIPTION

FIG. 1 is a front elevational view of the device utilized in converting electrical meter rate to currency rate showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is an isometric view thereof.

The broken line showing of numeral 88 is for illustrative purposes only and forms no part of the claimed design, while the electrical cord member has been shown broken away for ease of illustration.

FIG. 1

FIG. 2

FIG. 3

FIG. 4

*FIG. 5**FIG. 6**FIG. 7*
